C. POSTERNOCK

APPARATUS FOR WAVING HUMAN HAIR

Filed June 16, 1926

Inventor

Charles Posternock
By Chas Williamson

Attorney

UNITED STATES PATENT OFFICE.

CHARLES POSTERNOCK, OF PHILADELPHIA, PENNSYLVANIA.

APPARATUS FOR WAVING HUMAN HAIR.

Application filed June 16, 1926. Serial No. 116,440.

The object of my invention is to provide an apparatus or appliance for waving or curling human hair on the head which will most efficiently secure the desired result of producing waves or curls which will last or endure for the maximum period of time, promote the comfort of both the person whose hair is being operated on, and the convenience and speed of the operator, thus rendering his work less laborious and tedious, and so contributing in that way to the comfort of the person whose hair is being operated on, and to greatly simplify the apparatus, and thus reduce the cost of manufacture thereof, and diminish the liability of derangement, which results in temporary loss of use of the apparatus and expense by way of repair. My invention consists in whatever is described by or is included within the terms or scope of the appended claims.

In the drawings:

Fig. 1 is a view partly in side elevation and partly in perspective of enough of the apparatus to illustrate an embodiment of my invention;

Fig. 2 is a view in vertical section of the heating apparatus;

Fig. 3 is a detail view in perspective of the hair clamp.

By way of premise, it is desirable to say that the embodiment of my apparatus in its preferred form is the usual or ordinary one of a group or collection of electric heaters sufficient in number to treat a whole head of hair at one time, each heater operating, as is usual, upon a single strand of hair, and the collection of heaters being suspended from an overhead support or chandelier, or canopy. Each heater, as is common, comprises a structure within which is contained the twisted or curled strand of hair to be treated, moisture being provided for the generation of steam, but experience has shown that it is objectionable to use a closed chamber within the heater for the hair being treated from which escape of steam is prevented, and it will, therefore, be found to be a feature of my invention that the hair containing chamber is not closed, but protection is made at the outer end for the escape of steam, and at the end next the scalp, a moisture absorbing protecting device is used to catch steam passing from the end next the scalp, so as to prevent contact of

steam with the scalp to the discomfort and possible injury of the scalp.

My heater comprises two concentric tubes of substantially the same length, an outer one, 10, which constitutes the external casing, and an inner one, 11, which provides the central space or steaming chamber in which the hair wound or twisted upon a central rod, 12, as usual is placed. The tubes, 10 and 11, are of metal, preferably aluminum, and the inner tube, 11, has applied to its exterior, the electrical heating devices, as usual, to which current is supplied by flexible wires, 13, which at one end have a plug for detachable connection with a socket attached to and depending from an overhead canopy, the wires, 13, being, of course, of a length to reach to the head of the subject seated as usual in a chair.

It, of course, is understood that the tubular body formed by the concentric tubes, 10 and 11, must be separated from the curling rod, 12, until the hair has been wrapped or twisted upon said rod, and the customary solution containing flannel wrapped around the hair, and then the heater is placed endwise over the rod, and hair, and solution containing strips wrapped thereon, and the parts locked together in this assembly for the period required for the heating operation. At the bottom of the rod or the part next the scalp, a device is used to engage the strand of hair as close to the scalp as possible (sometimes a string is used to tie the strand to the rod), and when this device is of metal, it is important to prevent direct contact thereof with the scalp to avoid injury or discomfort from heat, and it is also necessary to protect the scalp from escaping steam, this being usually done by a disc of felt.

My hair engaging device comprises a plate which may be of disc form composed of two members, 14 and 15, respectively, which are secured together at the center by a stud, 16, which projects above the upper member, and is screw-threaded for a purpose explained hereinafter, the disc being provided with a radial slot, 17, which extends to the rim, and also comprises the slideable clamping device, 18, slidably connected with the disc and which at one end is formed into a hook, 19, which may be moved to and from the radial slot in the disc either to

clamp a strand of hair at the inner end of the slot preliminary to twisting the hair on the center rod or to release the strand of hair when the treating operation is over.

5 I make the disc of the two members as a convenient way of slidably connecting the clamping device therewith, the shank of such device being placed between the two members, one or both of which is provided

10 with a straight groove to contain and to guide the shank of the clamping device. The end of the clamping device opposite the hook projects sufficiently far from the disc to enable it to be readily caught hold

15 of by the fingers for manipulating it. When the strand of hair is gripped between the inner end of the radial slot and the clamping device, by the screwing of the center rod, 12, upon the threaded part of the stud,

20 16, a clamping grip will be exerted upon the slidable clamping device to prevent its accidental movement during the further use of the heater. There is no turning movement of the two members of the disc with reference

25 to one another, and as stated, the two members are used simply as a convenient way of connecting therewith the slidable clamping device. Secured to the side of the disc which comes next to the scalp in use

30 is a disc, 20, of felt for the purpose of absorbing escaping steam so as to prevent hurt or injury to the scalp from steam. Said felt disc has a radial slit that aligns with the radial slot in the disc members, 14 and

35 15, for the passage of the strand of hair into said radial slot.

A very important advantage of my hair engaging device due to the slidable hair clamp, is that there is no danger whatever

40 of hair being cut as exists in the case of the well known rotary disc type of hair engaging device, especially when pliers are used with such a device, the rotating discs in effect being blades of a pair of shears.

45 The inner and outer tubes, 10 and 11, are secured together at the bottom by an interposed ring, 21, and this ring and the adjacent ends of the tubes rest in contact with the upper metal disc 14, when the

50 heater is in operative position, and the locking together of the heater and the curling rod, and thus the entire assembly is effected by the very simple device of a knob, 22, having a projection or projections, 23, at

55 the upper end of the rod, which when the heater is slipped over the rod pass through a diametrical slot, 24, in the top of the outer tube, 10, and by a partial rotation of the heater with the knob, 22, and lugs, 23,

60 above such top the lugs and radial slot are turned out of alignment and the lugs engage a solid portion of the outer tube top. Unlocking is secured by a reverse operation. It will be seen that the act of turning the locking lugs out of alignment with the slot in

the top leaves the slot ends open, and thus provides that open condition of the heater which is necessary to allow the escape of steam at the top, and thus diminishes the likelihood of excessive discharge of the steam at the bottom and next the scalp of the individual.

The knob, 22, besides its rotary movement on the rod has an axial movement to enable it to be pulled upward to pass the radial lugs, 23, through the slot, 24, and it is so pulled against the pressure of a coil spring, 25, interposed between the shoulder on the rod, and the end of a chamber in the knob. The pressure of the spring tends to move the knob and its projections against the top of the outer tube with sufficient force to securely hold the parts together. When the knob, 22, is turned to place the lugs, 23, in alignment with the diametrical slot, 24, the spring automatically pushes the projections through the slot and thus automatically releases the locking connection so that the operation of removing the heater from the head is quickly and easily accomplished and without any discomfort to the subject whose hair is being treated. Inasmuch as the knob, 22, is pulled outward for the locking operation, it will be seen that the comfort of the person being treated is promoted as there is no thrusting or pushing motion against her head. A shoulder 26 on the rod, 12, that engages the inner side of the top of the outer tube, 10, holds the rod against outward movement when the knob, 22, is pulled outward against the pressure of the spring.

What I claim is:

1. A hair-curling appliance comprising hair-engaging means, composed of a plate having an opening for the passage of a strand of hair, and a slidable clamp device having a hook that is movable to and fro over said opening.

2. A hair-curling appliance comprising hair-engaging means, composed of a plate having an opening for the passage of a strand of hair, a slidable clamp device having a hook that is movable to and fro over said opening, and means to secure said clamp device in hair-clamping position.

3. A hair-curling appliance comprising a curling rod, a tubular heater through which the rod passes, and means detachably connecting heater and rod comprising a rotary latch device on the rod that is also movable longitudinally of the rod.

4. A hair-curling appliance comprising a curling rod, a tubular heater through which the rod passes, means detachably connecting heater and rod comprising a rotary latch device on the rod that is also movable longitudinally of the rod, and a spring that moves said latch longitudinally of the rod.

5. A hair-curling appliance comprising a curling rod, a tubular heater through which

the rod passes, and means detachably connecting heater and rod comprising a member slideable on the rod having a portion projecting laterally of the rod adapted to

5 overlap and engage an adjacent edge of the heater, and a spring acting to press said member into contact with said edge, the

heater having an opening through which said slideable member may pass when said member and said edge are out of engagement.

In testimony whereof I hereunto affix my signature.

CHARLES POSTERNOCK.
